UNITED STATES PATENT OFFICE

2,569,337

QUILTING FRAME

Thomas M. Rice, Providence, Ky.

Application August 12, 1949, Serial No. 109,965

2 Claims. (Cl. 45—24)

1

The present invention relates to new and useful improvements in quilting frames embodying a novel construction for holding the foundation web of the quilt in a taut position as the quilting progresses.

An important object of the invention is to provide a rear supply roller for the foundation web slidably mounted on the frame to regulate the size of the working area of the web and providing locking means holding the supply roller against rotation to hold the web taut during the quilting operation.

Another object is to provide pawl and ratchet locking means holding the supply roller from rotation and a lever for releasing the pawl from a substantially uniform position at the front of the frame regardless of the position of the supply roller.

A further object is to provide a device of this character of simple and practical construction, which is efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a top plan view;

Figure 2 is a side elevational view;

Figure 3 is an enlarged sectional view taken on a line 3—3 of Figure 1; and

Figure 4 is an enlarged sectional view taken on a line 4—4 of Figure 2.

Referring now to the drawings in detail, wherein for the purpose of illustration I have disclosed a preferred embodiment of my invention, the numeral 5 designates a stand generally which is composed of a pair of legs 6 having a base structure 7 at their lower ends and rigidly connected to each other adjacent their upper ends by a horizontal brace 8.

The inner sides of legs 6 at their upper ends are rabbed as shown at 9 and provided with bolts and wing nuts 10 pivotally supporting semi-circular plates 11 formed at the central lower edges of a pair of side rails 12 projecting forwardly and rearwardly of the legs for tiltable movement thereon.

The outer surfaces of rails 12 are formed with T-shaped tracks 13 received in correspondingly shaped slots 14 on the inner surfaces of slides 15 movable forwardly and rearwardly on the

tracks. The front portion of each slide 15 is provided with a pivoted dog 16 engaging teeth 17 on the upper edges of the rails and constructed to permit a free rearward sliding movement of the slides by ratcheting the dog along the teeth and to hold the slides from free forward movement.

The upper portions of slides 15 are formed with longitudinal slots 18 open at their rear ends and in which the ends of a rear supply roller 19 are received for rotation in the slots and held in position in the slots by vertical pins 20 positioned behind the roller.

One end of roller 19 is provided with a ratchet 21 engaged by a pawl 22 pivoted to the outer surface of an adjacent slide 15 by a pin 23 and with one end of the pawl extending downwardly. A horizontal pin 24 projects outwardly from the lower end of pawl 22 for selective engagement in notches 25 on the lower edge of a lever 26 which extends forwardly and is slidably supported in a guide 27 at the lower front edge of an adjacent rail 12. A stop 28 on the outer end of pin 24 holds lever 26 resting on the pin.

25 The front ends of rails 12 are also formed with slots 29 which are open at their front ends for receiving the ends of a front take-off roller 30 which is also provided with a ratchet 31 engaged by a pawl 32 pivoted to an adjacent rail.

30 In the operation of the device the customary foundation web 33 is wound on rear supply roller 19 which is then placed in the rear slots 18 of slides 15, the web extending forwardly from the bottom of roller 19 over front roller 30 for winding thereon. The slides 15 are moved longitudinally on rails 12 to expose a desired working area of the web and the slides are held in adjusted position by dogs 16 engaging teeth 17 on the rails.

35 40 The rear roller 19 is held stationary by pawl 22 engaging ratchet 21 and front roller 30 is likewise held stationary by pawl 32 engaging ratchet 31 to thus hold the web 33 taut.

When it is desired to unwind the web from 45 rear roller 19 onto front roller 30, lever 26 is pulled forwardly to release rear pawl 22 and front roller 30 is turned by a handle 34 at one end thereof, the front pawl 32 riding on ratchet 31 during such winding movement of the front roller 50 and rear pawl 22 gravitates into its engagement with ratchet 21 to lock the rear roller after a fresh area of the web has been moved into working position.

The pawl 22 is pivoted above its center so that 55 the lower end of the pawl will swing into a per-

pendicular position by gravitation to again engage the pawl.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A quilting frame comprising a stand including a pair of side rails, a slide on each rail, means locking the slides in adjusted position on the rails, a front roller journaled at the front portion of the rails, a rear supply roller journaled on the slides for feeding a web to the front roller, and pawl and ratchet means for the rear roller including a pawl on one slide rockable into releasing position, and releasing means for the pawl comprising a slidably mounted lever on one side rail extending to a position at the front of the stand

15

25

and having notches therein selectively engageable with said pawl in different positions of said slide.

2. A quilting frame comprising a stand including a pair of side rails having T-shaped tracks on their outer sides, a grooved slide fitting on each track, teeth on the upper edge of each rail, a pivoted dog on the inner side of each slide engaging the teeth to hold the slides in adjusted position on the tracks, a rear supply roller journaled on the slides, a front take-up roller journaled on the rails for winding a web thereon from the rear roller, and means locking the rollers against unwinding movement.
